COMBINED BUMPER, GRILLE AND LAMP UNIT FOR AN AUTOMOBILE

Charles F. Gitschlag, St. Clair Shores, Mich., assignor to Chrysler Corporation, Highland Park, Mich., a corporation of Delaware

Application June 10, 1959, Serial No. 56,287

Term of patent 7 years

(Cl. D14—18)

FIG. 3

FIG. 5

Fig. 1 is a front view of a combined bumper, grille and lamp unit for an automobile embodying my new design;

Fig. 2 is a top plan view thereof;

Fig. 3 is a side elevational view thereof; and

Figs. 4 and 5 are sectional views taken on the lines 4-4 and 5-5, respectively, of Fig. 1.

I claim:

The ornamental design for a combined bumper, grille and lamp unit for an automobile, substantially as shown.
